UNITED STATES PATENT OFFICE.

ERLING EGENÆS, OF CHRISTIANIA, AND OLE SANDVOLD, OF NOTODDEN, NORWAY,
ASSIGNORS TO NORSK HYDRO-ELEKTRISK KVAELSTOFAKTIESELSKAB, OF CHRIS-
TIANIA, NORWAY.

ELECTRIC FURNACE.

Application filed August 2, 1923. Serial No. 655,326.

To all whom it may concern:

Be it known that we, ERLING EGENÆS and OLE SANDVOLD, both subjects of the King of Norway, residing at Huitfeldts Gate 36, 5 Christiania, and at Notodden, respectively, both places in the Kingdom of Norway, have invented certain new and useful Improvements in Electric Furnaces; and we do hereby declare the following to be a full, 10 clear, and exact description of the invention, such as will enable others skilled in the art to which it appertains to make and use the same, reference being had to the accompanying drawings, and to letters or figures of 15 reference marked thereon, which form a part of this specification.

The present invention relates to electric furnaces with long stable light arcs, and a method of operating the same whereby gas 20 reactions are effected, the best possible utilization being made of the heat of the gases.

These furnaces usually operate in such a manner that the gases from the furnaces 25 pass through a boiler and then through the rest of the apparatus which, in the present case, it is unnecessary to describe.

One electrode of the furnace (the furnace cooler) is cooled with large quantities of 30 water. The greater part of the water runs away, while only a small quantity is used for feeding the boiler.

According to the present invention, the 35 heat of the gases can be better utilized by allowing the feed water of the boiler to pass under pressure first of all through the furnace cooler, whereupon it is forced through a feed valve into the boiler. Another advantage is, that without any risk of a leakage 40 occurring in the boiler, the feed valve can prevent water and steam from forcing its way into the furnace.

In order to prevent the water in the cooler 45 from penetrating into the furnace either on account of leakage or from a crack in the boiler, the water is allowed to pass through the furnace cooler at a somewhat lower pressure than the gas pressure in the furnace. In the event of a leakage, a little of the gas 50 would make its way into the cooling water. It would, however, by means of specially constructed controlling apparatus, be easy to observe when the gas starts to penetrate into the cooler and the furnace could then

be stopped. In the case of normal opera- 55 tion, the water is then conducted from the furnace cooler into a steam injector or some other kind of feeding apparatus, which forces the water into the boiler where the steam pressure is kept somewhat higher than 60 the gas pressure. Besides, reducing pressure in the cooler, the fire box and the fire tubes, it prevents the nitrous gases in the event of leakage, from forcing their way 65 into the boiler.

A form of apparatus for carrying out our 70 method is diagrammatically illustrated in the accompanying drawing, wherein 11 designates a furnace tube having apertures 9, through which air, preferably preheated, enters. 10 designates the isolated electrode, whereas the fire tubes 8 and the cooler 1 form the other electrode which may preferably be grounded.

Through a tube 6 in the cooler 1, the furnace 75 gases pass into the fire box 7, and from there to the fire tubes 8. The fire box 7 and tubes 8 are placed in the boiler 2. The cooling water is fed to the cooler by a conduit 12 and passes from the cooler, after 80 becoming heated, into a conduit 13 and is forced by a steam injector 5 through a feeding valve 3 into the boiler 2. If gas enters the feed water this can immediately be observed in a glass 4.

We claim—

1. In the operation of electric furnaces using long stable arcs and discharging into a steam boiler, the method which comprises 90 supplying cooling water to one of the electrodes and thereafter introducing said water, preheated by the heat abstracted from said electrode, into the boiler.

2. In the operation of electric furnaces using long stable arcs and discharging their 95 gaseous products into a steam boiler, the method which comprises cooling the upper electrode by water at a pressure less than the pressure of the furnace gases, feeding such water, preheated by the heat abstracted 100 from said electrode, into the boiler and separating furnace gases leaking into the cooling water.

3. In the operation of electric furnaces using long stable arcs and discharging their 105 gaseous products into a steam boiler, the method which comprises cooling the upper electrode by water at a pressure less than

the pressure of the furnace gases, feeding such water, preheated by the heat abstracted from said electrode, into the boiler, separating furnace gases leaking into the cooling water, and maintaining the steam pressure in the boiler higher than the pressure of gases in said furnace.

4. In a plant comprising an electric long arc furnace, a boiler for cooling the furnace gases including an electrode cooler, the com-

bination of means to feed water to said cooler under less pressure than the pressure of gases in the furnace, and means to supply the cooler with water preheated by said cooler.

In testimony that we claim the foregoing as our invention we have signed our names.

ERLING EGENÆS.
OLE SANDVOLD.
